UNITED STATES PATENT OFFICE.

DAVID GEDDES, OF BERKELEY, CALIFORNIA.

GRAIN WASHER, STONER, AND CONDITIONER.

Application filed April 19, 1926. Serial No. 102,904.

The object of my invention is to produce a simple and efficient mechanism by means of which grain, such as wheat, may be efficiently separated from dirt and other 5 foreign substances and may be subjected to a washing and, when desired, a steaming treatment.

The accompanying drawings illustrate my invention. Fig. 1 is a central vertical section; Fig. 2 a plan, and Fig. 3 a section on line 3—3 of Fig. 1.

In the drawings 10 indicates a suitable container or main body conveniently of a rectangular cross-section in its upper regions 15 with a conical bottom 11 having a clean-out opening 12 in its lower end, the casing being supported by suitable legs 13.

Arranged in the inverted cone 11 is a conical valve 14 provided at its lower outer 20 edge with a flexible packing strip 15 adapted to contact with the interior of cone 11, for a purpose which will appear. The valve 14 is provided with a stem 16 guided, top and bottom, in guides 17 and 18, and supported 25 at its lower end in a cap 19 threaded upon the lower end of a short pipe section 20 mounted in opening 12, the arrangement being such that vertical adjustment of the cap 19 will determine the relation between the 30 packing strip 15 and the interior of cone 11.

Jounaled in the upper part of body 10 is a hollow shaft 30 provided at one side with a radially extending apron 31 which, for a portion of its width is overlaid by guard 35 32 so as to produce a shoulder 33, the purpose of which will appear.

Leading from the interior of shaft 30 between apron 31 and guard 32 is a passage 34 extending the entire length of the apron.

Secured to the ends of shaft 30 and apron 40 31 are end plates 35, and bridging the space between these end plates, and secured to shaft 30, is an inclined bottom plate 36. Pivottally supported at 37, between the end 45 plates 35, is a depending valve plate 38 having a wear plate 39 attached to its lower edge and capable of contacting with the bottom plate 36. Attached to the valve plate 38 is a rod 40 upon which is mounted a counterweight 41, held in any desired adjustable position on rod 40 by means of the thumb screw 42, the arrangement being such that the counterweight serves to yieldingly 50 urge the wear plate 39 towards the bottom plate 36.

The parts 30 to 42, inclusive, form a

swinging hopper H into and through which the grain, to be drained, passes.

Secured to shaft 30 is a rearwardly projecting arm 51 connected by ball and socket 60 joint 52 with an adjusting rod 53 passed through a bracket 54 on main body 10 and provided with adjusting nuts 55 contacting bracket 54.

Formed through one side of body 10 at 65 about, or slightly above, the lower edge of apron 31 is a discharge opening 60 leading to a discharge spout 61.

Hinged at 62 along the lower edge of opening 60 is a reflector plate 63 which is 70 extended downwardly and inwardly into body 10 and provided at its free end with a rod 64 extended upwardly and rearwardly through a bracket 65 and provided with an adjusting nut 66 engaging the bracket. 75

An opening 67 is formed through the rear wall of the main body 10, above the opening 60, to permit freedom of movement of arm 51 and access to the adjusting nut 66.

Leading into body 10 is a water supply 80 passage 70 which will be connected to a suitable source of water supply and provided with a controlling valve.

Shaft 30 is provided with suitable bearings 75 journaled in suitable bearings 76 85 supported by the end walls of body 10 and the interior of this shaft is connected by a suitable swivel connection 77 with a valved pipe through which steam, water or other desired treating fluid may be introduced to 90 flow through passage 34 and over the exposed surface of apron 31.

The apron 31 may be adjusted to any desired angle relative to the normal water level W and held in adjusted position by nuts 55, 95 and the deflector plate 63 may be adjusted so as to form any desired width of throat between the free edge of apron 31 and the deflector plate or, if desired, the deflector plate may be brought into immediate contact with the free edge of the apron. 100

The operation is as follows:

A supply of water will be admitted through pipe 70 so as to maintain the water level W and a desired outflow through spout 61. 105 Deflector 63 will be adjusted to provide the desired throat at the free edge of apron 31 and cap 19 will be screwed upwardly so as to raise edge 15 a desired distance from the wall of cone 11. A stream of water 110 under considerable pressure will be admitted through pipe 30 so as to flow downwardly

- and outwardly along apron 31. The grain to be treated will be introduced in a continuous stream into the upper portion of the hopper H and valve plate 38 will yield under 5 the weight of the grain so that a comparatively thin and continuous stream of grain will flow downwardly and drop over the shoulder 33 onto the exposed upper surface of the apron 31 and into the body of water 10 within the structure and the stream of water issuing from passage 34. The combined action will result in driving the good grain through the upper regions of the water body towards and into spout 61 while heavier particles such as stones, dirt and other foreign substances will drop through the throat between apron 31 and plate 63 and settle downwardly onto valve 14 and thence into the lower part of cone 11. 15 The precise character of the separation will of course be dependent upon the relative adjustments of the parts, as will be clearly apparent.

When there has been a sufficient accumulation 20 of foreign substances in the lower part of cone 11, cap 19 may be withdrawn, whereupon valve 14 will seat itself in the cone 11 so as to retain the main body of water in the structure while at the same time permitting 25 the accumulated material in the lower part of the cone to be readily withdrawn without interrupting the operation of the device.

It will be understood that, instead of water, a stream of steam may be introduced into 30 shaft 30 and caused to traverse the apron 31, thus furnishing the necessary motive power for driving the grain from hopper H into the discharge spout 61, at the same time heating the grain to a proper degree. 35 This operation may be accomplished simultaneously with the separation of foreign substances in the manner previously described or, if the grain has been previously properly cleaned, the deflector plate 63 and free edge 40 of apron 31 may be brought close together so as to form a cup through which the stream of grain may pass from hopper H to discharge spout 61. There will, of course, be 45 a flow of water through the structure from pipe 70.

I claim as my invention:

1. A grain treating machine comprising a main hollow body having a hopper bottom, a grain receiving hopper mounted within 50 the upper region of said main body and having an apron over which the grain may flow, means by which a treating fluid may be caused to traverse said apron and to contact the grain stream thereon, a conical valve arranged within and to cooperate with the hopper bottom, and a closure for said hopper bottom arranged to support said valve.

2. A grain treating machine comprising a main hollow body in which a normal water 55 level may be maintained, a grain receiving

hopper mounted within the upper region of the said main body and having a delivery apron leading downwardly to said water level, means by which the pitch of the apron may be adjusted, means for determining 70 the thickness of the stream of grain from the hopper over the apron, and means by which a treating fluid may be delivered to the grain stream between said stream and the water in the main body. 75

3. A grain treating machine comprising a main hollow body in which a normal water level may be maintained, a grain receiving hopper mounted within the upper region of the said main body and having a delivery 80 apron leading downwardly to said normal level, means by which the pitch of the apron may be adjusted, and means by which a treating fluid may be delivered to the grain stream between said stream and the water in 85 the main body.

4. A grain treating machine comprising a main hollow body within which a normal water level may be maintained, a grain hopper arranged within the upper region of 90 said main body and comprising an apron over which a stream of grain may flow and means for determining the thickness of such stream, said apron depending below the normal water level, means by which a stream 95 of treating fluid may be introduced to the apron beneath the grain stream, and a deflector plate arranged within the main body to form a throat at the free edge of the apron. 100

5. A grain treating machine comprising a main body within which a normal water level may be maintained, a tubular shaft journaled in the upper region of said main body, means by which said shaft may be rotatably adjusted, an apron extending radially from said shaft and having its upper surface in communication with the interior of said shaft, a hopper bottom carried by the shaft and overlying the apron, and means 105 cooperating with said hopper bottom for limiting the thickness of grain stream passing over the hopper bottom to the apron. 110

6. A grain treating machine comprising a main body within which a normal water level may be maintained, a tubular shaft journaled in the upper region of said main body, means by which said shaft may be rotatably adjusted, an apron extending radially from said shaft and having its upper surface in communication with the interior of said shaft, a hopper bottom carried by the shaft and overlying the apron, a valve plate cooperating with said hopper bottom, and means for varying the resistance of said 115 valve plate. 120

7. A grain treating machine comprising a main body within which a normal water level may be maintained, a tubular shaft journaled in the upper region of said main 125

body, means by which said shaft may be rotatably adjusted, an apron extending radially from said shaft and having its upper surface in communication with the interior 5 of said shaft, a hopper bottom carried by the shaft and overlying the apron, means cooperating with said hopper bottom for limiting the thickness of grain stream passing over the hopper bottom to the apron, a guard plate adjustably mounted in the main body adjacent the free edge of the apron, and means by which said guard plate may 10 be adjusted towards and from the apron.

8. A grain treating machine comprising 15 a main body within which a normal water level may be maintained, a tubular shaft journaled in the upper region of said main body, means by which said shaft may be ro-

tatably adjusted, an apron extending radially from said shaft and having its upper 20 surface in communication with the interior of said shaft, a hopper bottom carried by the shaft and overlying the apron, a valve plate cooperating with said hopper bottom, means for varying the resistance of said 25 valve plate, a guard plate adjustably mounted in the main body adjacent the free edge of the apron, and means by which said guard plate may be adjusted towards and 30 from the apron.

In witness whereof, I have hereunto set my hand at Guadalajara, Mexico, this thirtieth day of July, A. D. one thousand nine hundred and twenty-six.

DAVID GEDDES.
